Attorneys.

UNITED STATES PATENT OFFICE.

ALONZO W. KANEY, OF CHICAGO, ILLINOIS, ASSIGNOR OF ONE-THIRD TO ROBERT E. L. JANNEY, OF CHICAGO, ILLINOIS.

PNEUMATIC SHOVEL.

1,351,425.

Specification of Letters Patent. Patented Aug. 31, 1920.

Application filed December 21, 1917. Serial No. 208,203.

To all whom it may concern:

Be it known that I, ALONZO W. KANEY, a citizen of the United States, residing at Chicago, in the county of Cook and State of Illinois, have invented certain new and useful Improvements in Pneumatic Shovels, of which the following is a specification.

This invention relates to an excavating shovel and has for its object the provision of means whereby labor may be more efficiently employed in excavating and handling material.

A further object of my invention is the provision of an excavating shovel provided with impact means for driving it into the material to be excavated, thus decreasing the necessary labor in excavating.

Further objects and advantages of my invention will be apparent as it is better understood by reference to the following specification when read in connection with the accompanying drawing illustrating the preferred embodiment thereof, in which—

Figure 1 is a front elevation of my excavator; and

Fig. 2 is a front elevation of a slightly different form of my invention.

Laborers engaged in excavating have heretofore been provided with ordinary shovels which are kicked into the earth by the user. This involves a large expenditure of energy, particularly, in hard soils. Such shovels are, therefore, inefficient in operation, the amount of earth moved at each operation being relatively insignificant. To overcome the inherent disadvantage of ordinary shovels as above set forth, I have provided a shovel having impact means which drives the shovel into the earth independently of the efforts of the user so that all his energy may be employed in lifting the shovel and conveying the contents to the proper place or receptacle.

One form of my invention is shown in the accompanying drawing, in which 5 indicates the shovel blade which may be of the form indicated or of any other suitable shape. The blade 5 is connected to a shank 6, preferably slightly tapered at its end. This shank extends into and snugly fits in the end of a pneumatic hammer 7, provided with the usual impact means adapted to strike

the end of the shank 6. The pneumatic hammer 7 may be fed from a suitable source of air under pressure (not shown) through a hose 8. Obviously when the blade of the shovel rests upon the earth and the pneumatic hammer 7 is operated, the blade will be steadily driven into the earth with a rapidity which depends upon the resistance met. The speed of operation is considerably greater than is possible where the shovel is kicked into the earth in the well-known manner.

Preferably a D or other form of handle 9 is secured to the upper end of the pneumatic hammer 7. The blade 5 may, if desired, be considerably larger than the blade of an ordinary shovel, the device being adapted for use by two individuals simultaneously. A stirrup 10 may be secured to the pneumatic hammer 7. By resting his foot in the stirrup the operator may hold the blade in contact with the material to be excavated. Obviously the form of the blade may be varied and may take the shape of a plow 11 (Fig. 2) which is advanced through the earth to turn up a furrow when held in proper position and actuated by the pneumatic hammer. The form of my invention illustrated in Fig. 2 makes a very desirable trenching tool.

From the foregoing it will be readily understood that I have perfected an excavating tool of simple and relatively inexpensive construction which presents numerous advantages over ordinary shovels and will enable the laborers, whether working singly or together to accomplish more work than has heretofore been possible and with less exertion.

Various changes may be made in the form and arrangement of the parts without departing from the spirit or scope of the invention or sacrificing any of its material advantages, the forms hereinbefore described being merely the preferred embodiments thereof.

I claim:

1. A pneumatic shovel comprising a blade, a shank for said blade, a power driven pneumatic hammer mounted on the upper end of the shank in alinement therewith and having impact means to engage the end of the shank, and a grip on the upper end of the

hammer, said shank, hammer and grip constituting the handle of the shovel.

2. A pneumatic shovel comprising a blade, a shank for said blade, a pneumatic hammer mounted on the upper end of the shank and comprising power driven impact means to engage the end of the shank, a grip on the

upper end of the hammer, and a stirrup secured to the hammer and arranged in adjacent relation to the blade.

ALONZO W. KANEY.
